UNITED STATES PATENT OFFICE.

THOMAS STENHOUSE, OF WASHINGTON, PENNSYLVANIA, ASSIGNOR, BY DIRECT AND MESNE ASSIGNMENTS, OF ONE-SIXTH TO ALEXANDER L. DUVAL D'ADRIAN, OF WASHINGTON, PENNSYLVANIA, AND ONE-SIXTH TO BERNHARD F. DRAKENFELD, JR., OF NEW YORK, N. Y.

METHOD AND APPARATUS FOR DRAWING GLASS CYLINDERS.

Application filed November 25, 1919. Serial No. 340,629.

To all whom it may concern:

Be it known that I, THOMAS STENHOUSE, a citizen of the United States, and resident of the town and county of Washington, State 5 of Pennsylvania, have invented new and useful Improvements in Methods and Apparatus for Drawing Glass Cylinders, of which the following is a specification.

This invention relates to an improved 10 method and apparatus for drawing glass cylinders, and has for its primary object and purpose to provide improved means whereby the speed of the draw may be accurately regulated and controlled in a uniform manner 15 for the drawing of cylinders of pre-determined diameter and thickness and in proportion to the rate of cooling of the molten glass.

In the art relating to the manufacture of 20 window glass, the glass is first drawn from a molten bath contained in a pot by means of a bait, a suitable lifting or hoisting apparatus being employed for raising the bait. When the fact is borne in mind that the 25 molten glass contained in the pot is cooling at a rate which is proportionate to the lowering of the body of glass in the pot, and the simultaneously raising or drawing of the cylinder, it is manifest that a corresponding 30 proportionate, evenly accelerated drawing speed is necessary in order to meet these conditions, whereby an accurately drawn cylinder of predetermined diameter and thickness will be formed. In the practice 35 of the art, it has been demonstrated that time and speed may be relatively employed to formulate a well-defined curve, and the essential concept of the present invention resides in the evolution of a composite curve, 40 and therefrom producing a part conforming to said curve whereby the operation of the hoisting apparatus may be automatically controlled. In this manner, when the temperature of the glass has been ascertained, a 45 proportionate and evenly accelerated rate of speed during the draw is maintained, thus eliminating the elements of error which are necessarily inherent in the old practice, where the skill of the operator is alone de- 50 pended upon to regulate and control the speed of the hoisting apparatus. Due to lack of skill, inadvertence or other human fallibility, the cylinder is frequently unevenly

drawn. As a complete insurance against such defective cylinders, and to provide 55 means for the definite automatic control of the hoisting or drawing apparatus, my present invention has been designed.

More particularly considered, the present improvement comprehends the provision of 60 a rheostat for controlling the operation of the hoisting apparatus, a rotatably mounted cam element, a variable speed motor geared to the cam element and means cooperating 65 with the cam element and actuated thereby to automatically operate the movable switch of the rheostat.

With the above and other objects in view, the present invention contemplates the provision of an improved method and apparatus 70 for drawing glass cylinders as above characterized, and the form, construction and relative arrangement of the several parts of such apparatus as will be herein-after more fully described, illustrated in the 75 accompanying drawings and subsequently incorporated in the subjoined claims.

In the drawing wherein I have illustrated one practical embodiment of my invention, and in which similar reference characters 80 designate corresponding parts throughout the several views, Fig. 1 is a front side elevation, and Fig. 2 is a top plan view.

For purposes of illustration I have disclosed an apparatus in the accompanying 85 drawing consisting of a rheostat 1, which is electrically connected to a motor (not shown), which in turn operates a bait hoisting apparatus of the usual form. To the spindle or shaft 2 of the control lever 3 of 90 the rheostat a spur gear 4 is keyed or otherwise fixed. This gear meshes with a rack 5. A roller 6 is mounted upon one end of the rack bar and has peripheral contact with a cam 7 which is fixed upon a shaft 8. On 95 this cam shaft, a worm gear 9 is keyed and is driven by the worm 10 on the shaft 11. A worm wheel 12 on said shaft is engaged by a worm on the motor shaft 13. The speed of the motor 14 is controlled and regulated by 100 means of a rheostat 15 having the usual switch lever 16.

The peripheral outline for the cam 7 is determined by first placing a card or disk, shown at D in dotted lines, in the place to be 105 occupied by the cam and engaging the

point of a pencil or other marker with the surface of this disk in the position corresponding to the contact roller 6 in readiness for the start of the drawing operation. The 5 rheostat lever 16 is then moved to a position to set the motor 14 in operation, the speed of operation of this motor being predetermined in accordance with the known temperature of the molten body of glass from 10 which the cylinder is to be drawn. At the same time the operator moves the lever 3 of the rheostat 1, so that the hoisting apparatus will be operated at a suitable speed to form a cylinder of the required diameter and 15 thickness. In this operation of the rheostat lever 3, the rack 5 is shifted and a curved line will be drawn by the pencil or marker on the surface of the disk D. This line is indicative of the decrease in temperature or 20 cooling of the molten glass bath during the drawing operation. This preliminary drawing operation is repeated a number of times, so that a number of cards are thus marked with the cooling curve. From these cards a 25 composite curve is made which is indicative of the mean rate of cooling of the molten glass in the bath. The cam element 7 is now constructed with its peripheral outline corresponding to the mean cooling curve which 30 has been first ascertained in the manner above stated. It is now only necessary to fix this cam element 7 on the shaft 8 in contact with the roller 6 on the end of the rack 5. In the subsequent drawing operations, 35 the drawing of the cylinder will proceed at the proper rate of speed and at a speed acceleration which is proportionate to the decreasing temperature of the bath. Thus, when the molten glass has been delivered 40 to the pot by the ordinary means provided for this purpose and the bait has been lowered into the molten glass and left in contact therewith for a sufficient time to cause the glass to adhere to the bait, the operator 45 moves the lever 16 into operative contact with the rheostat 15, which sets the motor 14 in operation. Through the medium of the worm gearing, motion is thus imparted to the cam 7 and as this cam is in contact with 50 the roller 6, the rack 5 is given a rectilinear movement, and through the medium of the gear 4, the lever 3 is moved into engagement with the resistance contacts 17 on the rheostat 1, and said lever advances at the required speed to form a cylinder of the desired length and maintain the predetermined 55 diameter and thickness thereof.

It will be apparent to those skilled in the art that the temperature of the glass is a 60 determining factor in governing the rate of speed at which the bait must be raised to form the cylinder. It is also manifest that the speed of this operation must be accelerated proportionately throughout the 65 length of the draw to the temperature of

the glass. Accordingly, when the temperature of the glass is ascertained, it is only necessary to position the lever 16 at a suitable point on the rheostat 15, so that the motor 14 will be driven at the necessary speed to insure the desired proportionate acceleration in the speed of draw through the medium of the cam 7.

By first ascertaining the mean cooling curve of the glass in the manner above described, this cam 7 may be made in a plurality of forms in accordance with the desired diameter and thickness of the cylinder to be drawn.

From the foregoing description considered in connection with the accompanying drawing, my improved method of drawing glass cylinders and the means whereby this method may be successfully practiced will be clearly and fully understood. It will be appreciated that the invention in operation will be accurate and reliable, and as the mechanism which I have devised for governing or controlling the speed of draw for the cylinder, is exceedingly simple, it will be apparent that the invention can be produced at comparatively small manufacturing cost.

I have herein shown and described one embodiment of my invention which I believe to be satisfactory in practical use, but it will be understood that the device may also be exemplified in numerous other alternative modifications, and I therefore do not desire to be restricted to the specific example above referred to, but reserve the privilege of resorting to such legitimate changes in the form, construction and arrangement of the several parts as may be fairly embodied within the spirit and scope of the invention as claimed.

I claim:

1. The method of producing articles of predetermined form and thickness, which consists in drawing the article from a bath of molten plastic material and proportioning the speed of acceleration of the drawing operation according to the mean rate of cooling of the molten plastic material in the bath.

2. In mechanism to control the speed of acceleration of drawing glass cylinders, a movable part controlling the operation of the drawing apparatus and mechanism to automatically actuate said movable part at a predetermined rate of speed to operate the drawing apparatus and uniformly increase the speed of draw at a rate predetermined by the temperature of the material and the diameter and thickness of the cylinder.

3. In mechanism to control the speed of acceleration of drawing glass cylinders, a movable part controlling the operation of the drawing apparatus, and mechanism to automatically actuate said movable part, including a rectilinearly movable element, a

cam coacting with said element, and means to operate said cam at a predetermined speed whereby the speed of the drawing operation is automatically increased in proportion to 5 the decrease in temperature of the glass.

4. In mechanism to control the speed of acceleration of drawing glass cylinders, drawing apparatus including a movable part and mechanism to automatically actuate 10 said movable part comprising an element operatively connected with the movable part of the drawing apparatus, a cam co-acting with said element and of a form determined by the diameter and thickness of the cylinder 15 to be drawn, and means for rotating the cam at a speed predetermined in respect to the temperature of the glass.
5. In mechanism to control the speed of acceleration of drawing glass cylinders, a 20 movable part controlling the speed of operation of a drawing apparatus, and mecha-

nism to automatically actuate said movable part including a motor driven cam having a fixed peripheral outline predetermined with respect to the temperature of the glass to 25 thereby effect a proportionately accelerated speed of operation of the drawing apparatus.

6. In the art of glass manufacture, mechanism to control the speed of acceleration of operation of a glass cylinder drawing apparatus including a cam having a fixed predetermined curvilinear outline conforming to the cooling curve of the glass during the drawing operation, and designed 30 to effect an accelerated increase in the speed of the draw in accordance with the desired diameter and thickness of the cylinder.

In testimony that I claim the foregoing as my invention, I have signed my name 35 hereunder.

THOMAS STENHOUSE.
